Edgar V. St. B.

UNITED STATES PATENT OFFICE.

JOSEPH NEEDHAM, OF NEW YORK, N. Y.

VALVE DEVICE.

1,402,527.

Specification of Letters Patent.

Patented Jan. 3, 1922.

Application filed June 9, 1920. Serial No. 387,605.

To all whom it may concern:

Be it known that I, JOSEPH NEEDHAM, a citizen of the United States, and residing at New York, in the county of New York 5 and State of New York, have invented certain new and useful Improvements in Valve Devices, of which the following is a specification, such as will enable those skilled in the art to which it appertains to make and 10 use the same.

This invention relates to valve devices and particularly to devices of this class designed for use in connection with apparatus employing high pressure gases or liquids; 15 and the object of the invention is to provide a valve device of the class specified which is automatically opened by the passage of a liquid or gas therethrough in one direction at a predetermined pressure, and which is 20 also automatically closed by gravity and back pressure; a further object being to provide a means for relieving the back pressure in the device or permitting of the passage of a liquid or gas therethrough in opposite directions; a still further object being 25 to provide means for controlling and regulating the discharge of the back pressure of the liquid or gas through the valve device; and with these and other objects in 30 view the invention consists in a valve device of the class and for the purpose specified, constructed and operating as herein-after described and claimed.

The invention is fully disclosed in the 35 following specification, of which the accompanying drawing forms a part, in which the separate parts of my improvement are designated by suitable reference characters in each of the views, and in which:—

40 Fig. 1 is a side and sectional view of my improved valve device in its normal or closed position; and,

Fig. 2 a partial section on the line 2—2 of Fig. 1.

45 In Fig. 1 of the drawing I have shown at 5 the body portion of the device which is provided at its opposite sides with hexagonal extensions 6 and 7 internally threaded to receive pipes, couplings and the like in 50 the usual manner. The body of the device is also provided with an upwardly directed tubular extension 8 having a detachable closure cap 9.

55 The opposite side walls of the extensions 8 of the body 5 are provided with bosses 10 and 11, the boss 10 being threaded to receive

a sleeve 12, the outer end portion of which is closed by a plug 13. The boss 11 is threaded to receive a plug 14 having an external nut portion 15 and the inner end of which is 60 recessed as shown at 16 to receive a trunnion 17 at one end of a tubular shaft 18, which is mounted transversely of the body of the device between the bosses 10 and 11. A threaded shaft 19 is mounted in the tubular shaft 18 and the outer end portion 20 of which has a bearing in the sleeve 12, and is also provided with an angular extension 21 which extends into the sleeve 12 and upon which a suitable key device is adapted 65 to be placed when the plug 13 is removed for rotating the shaft 19.

The shaft 19 is provided adjacent to its outer end with an enlarged beveled portion 22, which operates in connection with a 75 beveled face 23 on the corresponding end of the tubular shaft 18 to hold said shafts together within the body portion and in common alinement. The inner end of the shaft 19 is provided with an enlarged portion 24 80 which fits within the shaft 18 and is provided with an annular groove 25. The outer end portion of the shaft 18 is beveled as shown at 26, and this bevel operates in a bevel seat 27 in the recess 16 of the plug 14, 85 and this construction in connection with the outer end portion of the shaft 19, or the mounting thereof, permits of the free rotary oscillatory movement of the shafts 18 and 19 in the sleeve 12 and plug 14. 90

Mounted on the shaft 18 is an arm 28 which is secured thereto by a screw 29 passed through the head portion 30 of said arm through the shaft 18 and into the annular groove 25 on the enlarged portion 24 95 of the shaft 19. The free end portion of the arm is provided with a circular aperture 31.

Movably mounted on the shaft 19 within the tubular shaft 18 is a block 32 which is threaded to correspond with the thread on 100 the shaft 19, and said block is provided with an outwardly directed arm 33 which passes through and operates in an elongated aperture 34 in the tubular shaft 18.

The arm 28 carries a main valve member 105 35 which comprises a disk 36 provided at one side thereof with an annular flange 37 inwardly of which said side of the disk 36 is provided with a disk 38 of comparatively soft metal or fibrous material, which operates 110 in connection with a valve seat 39 in the body portion 5 of the device to form a gas and

liquid-tight seal. The valve member 35 is mounted on a sleeve 40 which passes through the aperture 31 in the arm 28 and is secured to said arm in any desired manner. The 5 sleeve 40 is provided centrally thereof with a flange 41 against which the disk 36 rests and outwardly of the flange 41, the sleeve 40 is externally threaded as shown at 42 to receive a thimble-shaped member 43, the inner end of 10 which is flanged as shown at 44 and serves to hold the disks 36 and 38 firmly upon the sleeve 40.

Slidably mounted in the thimble-shaped member 43 is a supplemental valve member 15 45, the inner end of which is provided with an enlarged head 46 which operates in connection with the outer end portion of the sleeve 40 to close the communication between said sleeve and the thimble-shaped member 20 43. The thimble-shaped member 43 is provided about the periphery thereof with a plurality of apertures 47 which, when the supplemental valve member 45 is open, places the main chamber 48 of the valve device or 25 the body portion 5 thereof in communication with a supplemental chamber 49 in said body portion.

The supplemental valve member 45 is tubular in form, as shown at 50, and mounted in 30 the outer end or head portion 51 of said valve, which protrudes beyond the thimble-shaped member 43, is a screw 52 or other attaching device to which one end of a spiral spring 53 mounted within the tubular portion 35 50 of the valve 45 is secured. Connected with the other end of the spring 53 is a wire or cable 54, which passes around a pulley 55 rotatably mounted in the inner end portion of the sleeve 40, and said wire or cable passes 40 upwardly through a slot 56 in said sleeve and around another pulley 57 mounted on the screw 29, and the other end of said wire or cable is secured to the outwardly directed arm 33 of the block 32.

45 From the foregoing description the operation of my improved valve device will be readily understood when taken in connection with the accompanying drawing and the following statement. The position of the main 50 valve member 35 and supplemental valve member 45 shown in Fig. 1 is their normal or inoperative position, the valve 35 being held upon its seat by gravity, while the valve 45 is held upon its seat 58 by the spring 53. When 55 liquid or gas under pressure is introduced into the chamber 49 the valve member 35 will be raised from its seat 39, and said liquid or gas will pass into the chamber 48 and through the valve device. In the presence of 60 excess pressure in the chamber 48, or a pressure greater than that in the chamber 49, the valve 35 will be automatically closed, and when the pressure in the chamber 48 reaches a predetermined degree, the degree being determined by the tension of the spring 53, the

excess pressure will automatically open the valve member 45 to place the chamber 48 in communication with the chamber 49 through the apertures 47 in the thimble-shaped member 43, and a by-pass port or passage 59 70 formed by the sleeve 40, thus allowing the excess pressure in the chamber 48 to escape into the chamber 49.

From the foregoing it will be seen that the supplemental valve 45 acts in the manner of a relief valve to relieve the pressure in the chamber 48 to prevent accidents that might occur in the presence of too great a pressure in said chamber. It will also be apparent that by rotating the shaft 19 by means of a 75 suitable key which is placed on the angular end portion 21 of said shaft, the block 32 may be moved longitudinally of the shaft 19 within the tubular shaft 18 to either increase or decrease the tension of the spring 53 by pulling or slackening the cable 54, which is attached to the free end of said spring. With 80 this attachment the exact pressure at which the valve 45 will open may be positively determined.

It will also be understood that while I have shown a particular form of valve body and certain details of construction for supporting and actuating the separate valve members which I employ I am not necessarily limited to these details, and various changes in and modifications of the construction herein shown and described may be made, 95 within the scope of the appended claims, without departing from the spirit of my invention or sacrificing its advantages.

Having fully described my invention, what I claim as new and desire to secure by Letters Patent, is:—

1. A valve device of the class described 105 comprising a hollow body portion, a valve seat in said body portion, an arm pivotally mounted in the body portion, a sleeve mounted in the free end portion of said arm, a main valve mounted on said sleeve and 110 adapted to operate in connection with the valve seat in the hollow body portion for dividing said body portion into independent chambers, said sleeve forming a communication between said chambers, a supplemental 115 valve movably mounted in connection with said sleeve and adapted to normally close the communication between said chambers through said sleeve, and adjustable means 120 for controlling the movement of said supplemental valve.

2. A valve device of the class described 125 comprising a hollow body portion, a valve seat in said body portion, an arm pivotally mounted in the body portion, a sleeve mounted in the free end portion of said arm, a main valve mounted on said sleeve and 130 adapted to operate in connection with the valve seat in the hollow body portion for dividing said body portion into independent

- chambers, an apertured thimble-shaped member mounted in connection with said sleeve, a supplemental valve movably mounted in connection with said thimble-shaped member and adapted to operate in connection with said sleeve to normally close the communication between said chambers through said sleeve, a spring connected with said supplemental valve, a threaded shaft mounted in the pivoted end of said arm, and means in operative connection with said shaft and said spring whereby the rotation of said shaft will increase or decrease the tension of said spring.
- 15 3. A valve device of the class described comprising a hollow body portion, a valve seat in said body portion, an arm pivotally mounted in the body portion, a sleeve mounted in the free end portion of said arm, a main valve mounted on said sleeve and adapted to operate in connection with the valve seat in the hollow body portion for dividing said body portion into independent chambers, an apertured thimble-shaped member mounted in connection with said sleeve, a supplemental valve movably mounted in connection with said thimble-shaped member and adapted to operate in connection with said sleeve to normally close the communication between said chambers through said sleeve, a spring connected with said supplemental valve, the pivoted end of said arm being tubular in form, a threaded shaft rotatably mounted in the tubular portion of said arm, a block mounted to move longitudinally of said shaft, means connected with said block and with said spring whereby the rotation of said shaft will increase or decrease the tension of said spring.
- 40 4. A valve device of the class described comprising a suitable body portion provided with a valve seat, a member pivotally mounted in the body portion and having a free end portion provided with a sleeve, a main valve member mounted in connection with said sleeve and adapted to operate in connection with said valve seat to divide the body into independent chambers, an apertured member mounted in connection with said sleeve at one side of said valve, a supplemental valve movably mounted in said apertured member and adapted to operate in connection with said sleeve to normally close the communication between said chambers through said sleeve, tensional means for normally holding said supplemental valve in a closed position and means adjustably mounted in the valve device and in operative connection with said tensional means for controlling and regulating the tension thereof.
- 45 5. A valve device of the class described comprising a suitable body portion provided with a valve seat, a member pivotally mounted in the body portion and having a free end portion provided with a sleeve, a main valve member mounted in connection with said sleeve and adapted to operate in connection with said valve seat to divide the body into independent chambers, an apertured member mounted in connection with said sleeve at one side of said valve, a supplemental valve movably mounted in said apertured member and adapted to operate in connection with said sleeve to normally close the communication between said chambers through said sleeve, a spring connected with said supplemental valve, a threaded shaft mounted in the pivoted end portion of said first named member, a block mounted to move longitudinally of said shaft, means connected with said block and with said spring whereby the rotation of said threaded shaft may increase or decrease the tension of said spring, and means whereby a suitable tool may be inserted into the body portion of the valve device to engage and rotate said threaded shaft.
- 50 6. A valve device of the class described comprising a suitable body portion provided with a valve seat, a member pivotally mounted in said body portion and having a free end portion provided with a sleeve, a main valve detachably mounted on said sleeve and held in position by an apertured member detachably mounted in connection with said sleeve at one side of said valve, said main valve being adapted to divide the body portion into independent chambers, and a supplemental tensionally controlled valve movably mounted in said apertured member and adapted to operate in connection with said sleeve to normally close the communication between said chambers through said sleeve.
- 55 In testimony that I claim the foregoing as my invention I have signed my name in presence of the subscribing witnesses this 8th day of June, 1920.

JOSEPH NEEDHAM.
